The ornamental design for a vial, as shown and described.

(51) **LOC (8) Cl.** 24-01

DESCRIPTION

(52) **U.S. Cl.** D24/224

FIG. 1 is a front perspective view of a vial illustrating a variant of the present design;

(58) **Field of Classification Search** D24/216–230,

FIG. 2 is a top plan view of the vial of FIG. 1;

D24/110, 121; D9/439, 440, 503, 521; 422/99–102,

FIG. 3 is a bottom plan view of the vial of FIG. 1;

422/104; 435/288.1, 288.2, 294.1, 295.1;

FIG. 4 is a left side view of the vial of FIG. 1;

356/246; 215/227, 296; D3/203.1, 203.2

FIG. 5 is a front view of the vial of FIG. 1;

See application file for complete search history.

FIG. 6 is a cross-sectional view of the vial of FIG. 1 taken along the line 6—6 as shown in FIG. 4;

(56) **References Cited**

FIG. 7 is a top perspective view of the vial of FIG. 1, with the cap shown in an open position; and,

U.S. PATENT DOCUMENTS

FIG. 8 is a bottom perspective view of the vial of FIG. 1, with the cap shown in an open position.
